CHARLES P. WATSON, OF PHILADELPHIA, PENNSYLVANIA, ASSIGNOR TO WATSON ARMS COMPANY, INC., OF PHILADELPHIA, PENNSYLVANIA, A CORPORATION OF DELAWARE.

DETONATING MEANS FOR FUSES.

1,316,608.

Specification of Letters Patent. Patented Sept. 23, 1919.

Application filed February 21, 1917. Serial No. 150,104.

To all whom it may concern:

Be it known that I, CHARLES P. WATSON, a citizen of the United States, residing at Philadelphia, in the county of Philadelphia and State of Pennsylvania, have invented 5 certain new and useful Improvements in Detonating Means for Fuses, of which the following is a specification.

My invention relates to means employed 10 for detonating charges of explosive, and is designed particularly to be used in connection with impact fuses for shells containing high explosives, though it is not limited to this use.

15 It is now the common practice to load the shell that is fired from a gun with a large charge of high explosive which is detonated by means of a device called a fuse or detonator. The fuse usually contains a charge 20 of some high explosive that is not sensitive to shock, such as tri-nitro toluol, this charge being in turn ignited or detonated by a small charge of an explosive that is in its nature sensitive both to heat and shock, 25 fulminate of mercury being most commonly employed for this purpose. Fulminate of mercury explodes with great violence, and under ordinary conditions is highly sensitive, and the dangers of a premature ex- 30 plosion of a shell are largely due to its presence. It is readily fired by flame, by heat, or by percussion. A cap or primer arranged to be exploded under determined 35 conditions is usually employed for igniting the fulminate charge, the flame from the primer being the immediate exciting agent. Owing to the dangerous properties of fulminate of mercury, many and ingenious inventions have been made to render safe 40 fuses and shells in which a detonating charge of this material is carried.

It has long been known that if fulminate of mercury be highly compressed, that is by pressure from 5000 to 15000 pounds per 45 square inch, or even more, it loses its dangerous properties to a large degree, and it has been supposed that when compressed about 15000 pounds per square inch it becomes "dead"—that is, so inert that it 50 cannot be exploded by percussion or heat. When thus compressed it will burn, but without explosive effect; and it may be subject to exceedingly rough usage and severe blows without danger of detonation.

It has, therefore, been considered that fulminate of mercury, when thus highly compressed, is unsuitable for use as a detonating charge in fuses or for other similar purposes.

I have discovered, however, that fulminate of mercury when highly compressed so as to be in condition to be handled with comparative safety, as from 10,000 to 15,000 pounds per square inch, or even more highly, may be fired or detonated with great certainty by the use of a properly constructed firing pin; and the results which I have obtained are entirely satisfactory and remarkable in their effectiveness. Thus I have found that if a charge of highly compressed 70 fulminate of mercury be acted upon by a firing pin having a sharp point that will readily puncture such charge of explosive, and having also sharp edges leading from the point of said firing pin, such as would be formed by sharpening a square, triangular, or other polygonal rod to a sharp point, the compressed explosive charge is detonated.

I have made many experiments and obtained by the means stated uniformly good results and instant and violent detonations of the compressed charges. In my experiments I have attempted to detonate or explode fulminate of mercury highly compressed as described, by means of firing pins, the ends of which were flat, and by means of firing pins the ends of which were rounded or blunt, and the results have been most unsatisfactory, either no detonations 85 whatever taking place, or if any were secured, they were uncertain, more failures than successful firings occurring.

I have also discovered, as the result of numerous experiments, that while a round 95 or blunt ended firing pin operates successfully with fulminate of mercury which is but slightly compressed, as, say, to about 300 pounds per square inch, a sharp pointed firing pin does not work well with charges of 100 fulminate of mercury thus lightly compressed.

In the use of my invention it becomes unnecessary to use a cap or primer as a means for firing the detonating charge of 105 sensitive explosive, as the firing pin punctures and engages directly with the highly compressed mass of explosive itself. A shell

provided with my invention has the element of danger due to premature explosions very greatly reduced, for no degree of heat, or even the direct contact of flame with the detonating charge will cause the explosion thereof, and any shock that the main charge of the shell will withstand, the detonating charge of compressed fulminate of mercury will withstand.

10 My experiments lead me to believe that it is only when a highly compressed, and hence relatively safe, charge of fulminate of mercury is pierced by a firing pin such as I have described that it detonates. When, however, 15 it is thus detonated, it operates with exceeding violence and quickness far beyond that of explosives uncompressed, or but slightly compressed.

10 My invention may be practised in many 20 different ways. I ordinarily prefer to compress the charge of detonating explosive within a small metal container of sufficient strength, the end of which is left open except for a thin cover or closing cap of some 25 kind. This container is then, at the instant detonation of the charge is desired, brought into co-operative relationship with a firing pin of suitable construction, either through the moving of the firing pin, the container 30 for the explosive charge being stationary, or through a movement of the container, the pin being stationary, or through the simultaneous movements of each toward the other, so that the pin is caused to puncture the 35 charge of compressed explosive, piercing the closing cap, or even the wall of the container in so doing.

10 In the accompanying drawings I have 40 illustrated one form of my invention. Referring to such drawings,

Figure 1 is a longitudinal view of a portion of a fuse provided with my invention.

Fig. 2 is a transverse sectional view taken on the line II II of Fig. 1, the parts being 45 enlarged.

Figs. 3 and 4 are different forms of the firing pin when constructed so as to adapt them to be moved to engagement with the detonating charge of compressed explosive.

50 Fig. 5 is a longitudinal view of a container for a charge of compressed explosive.

Fig. 6 is a sectional view conventionally representing a press for loading the containers with the explosive.

55 Fig. 7 is a view of the container after it has been loaded or removed from the press, and with the closing cap in place, but not confined.

Fig. 8 is an end view of the completed 60 container, the open end of the container being crimped over the edge of the cap to hold it in place.

Fig. 9 illustrates another form of the firing pin from that shown in the other views.

65 In Fig. 1 I have illustrated my invention

applied to a detonator having the general features of construction illustrated in my Patent 1,197,414 of September 5, 1916. Referring to this view, 2 designates the main body of the detonator, 3 the chamber in 70 which is located the booster charge, and 4 the chamber in which is located the detonating charge of compressed sensitive explosive. A partition 5 separates these chambers, and through this partition is a perforation 6. Extending from the partition into the chamber 3, and preferably integral with the partition, is a tube 7. The walls of the perforation 6 and the tube 7 constitute the runway for the capsule 8, containing the 80 highly compressed charge of fulminate of mercury or other sensitive detonating explosive. The capsule 8 is seated in a chambered plug 9. A valve device 10 is arranged to cover the opening of the passage 6, on 85 the side toward the chamber 4. The nature of this valve device is quite immaterial so far as this present invention is concerned, that represented being similar to the valve shown in my aforesaid patent and arranged 90 to move so as to open the runway for the passage of the capsule 8 by the action of centrifugal force developed by the rotation of the shell when in flight.

11 designates the firing pin. In the form 95 of invention represented in Fig. 1, it is carried at the forward end of the tube 7. This pin is pointed and is formed with a series of edges 12, extending from the point to the base. The form of the pin represented in 100 Fig. 1 is square in cross section, and this is the form that I have found to be entirely satisfactory, and therefore prefer to use. However, pins of other forms may be used if they have the characteristics mentioned— 105 namely, a pointed end that will pierce the mass of compressed explosive and edges extending from the point toward the base of the pin. In Fig. 4 the pin shown is triangular in cross section, and it is apparent, from 110 what has been said, that other forms than those mentioned may be used and will readily suggest themselves to those skilled in the art.

115 In the arrangement shown in Fig. 1, the firing pin is held stationary, relative to the other parts of the fuse and the container or capsule carrying the charge of compressed detonating explosive is movable. By means, not shown in the drawings, and which may 120 be of a widely varied character, the capsule is projected forward and toward the firing pin at the instant the explosion of the shell is desired, as for instance upon impact thereof with the target. I have represented 125 a charge of black powder 13, which is fired by any suitable mechanism, as being the propelling means for urging the capsule into the runway and toward the firing pin.

The positions of the capsule or container 130

8 and the firing pin might be reversed, as has been already herein suggested, the capsule then being held stationary and the firing pin being movable toward the capsule; 5 and in Figs. 3 and 4 I represent firing pins 11 supported at the ends of cylindrical bodies 14, that are movable so that they may carry the firing pins into engagement with the compressed charges of explosive, and 10 are sufficiently ponderous to give the firing pins sufficient inertia to insure their puncturing and detonating such charges. If such a form of firing pin were employed in an arrangement like that shown in Fig. 1, the 15 body 14 carrying the firing pin at its forward end would be loaded into the plug 9 in place of the capsule 8, shown in Fig. 1.

In view of the characteristics possessed by highly compressed fulminate of mercury, 20 as hereinbefore set forth, it is feasible and safe to support a detonating charge thereof in immediate proximity to the booster charge of a fuse, a practice that would be highly objectionable and dangerous, if ful- 25 minate of mercury in the form now usually employed in fuses were used.

In Fig. 6 I represent, in a diagrammatic and conventional manner, means for loading a capsule or container 8 with a charge of 30 explosive 15. The capsule is a tubular container preferably formed of thin steel, cylindrical in shape and with one of its ends closed. Into this is compressed a charge of the explosive by means of a suitable press 35 16 adapted to give the desired compression to the explosive charge. Due to the high compression to which the charge 15 is subjected, I am able to load very much more of the explosive into a container of a given 40 size than has heretofore been possible. Heretofore fuses have been provided with movable detonating capsules containing 18 grains of fulminate—this being considered an exceedingly large charge. In practising my 45 invention I load 28 grains into a capsule of less size than that heretofore employed to carry 18 grains. The result is that not only are the dangers incident to the loading of the fuses and shells, and to the handling, 50 storing and firing of the latter very greatly reduced, but the effectiveness of the detonating charge is greatly increased, due partly to the fact that it is feasible to use a much larger charge thereof, and also to the fact 55 that when such a charge is highly compressed, as I have described, it detonates with exceeding violence when it does detonate.

After the charge 15 is compressed into the 60 capsule or container 8, the latter is removed from the press 16, and a cap or cover 17 is placed in the open end of the capsule, covering the charge, as represented in Fig. 7. This cap or cover is preferably formed 65 of some suitable, thin, soft metal, such as

copper. The next step in the manufacture is to crimp the edges of the open end of the capsule over the cap 17, as represented at 18 in Fig. 8.

When the firing pin and the charge of 70 compressed explosive come into coöperative relation to cause the detonation of the latter, the firing pin punctures the cap 17 and engages directly with the charge of compressed explosive. 75

I am not able to positively state why an explosive, such as fulminate of mercury, that is exceedingly sensitive under low compressions, but is highly inert under very high compressions, may be successfully and 80 certainly detonated if punctured by a sharp pin having edges, while it will not be detonated if a cylindrical, round ended pin be employed. The most plausible theory to me is that the sharp end of the firing pin permits it to puncture the mass of highly compressed explosive and therefore come into intimate engagement therewith, and the sharp inclined edges 12 of the pin, engaging directly with the particles of the compressed 85 charge rupture them in such manner and under such conditions that detonation takes place. 90

Other explosives having characteristics more or less similar to fulminate of mercury, that is the property of being, under ordinary conditions and slight compression highly sensitive to flame, heat and shock, but which, when highly compressed, become 95 relatively inert and hence safe to handle, 100 such as lead azid and silver azid, copper azid, fulminate of gold, sulfo-cyanid of lead and fulminate of gold may be successfully detonated, when highly compressed, if treated 105 in the manner herein described with particular reference to the use of fulminate of mercury. 110

In Fig. 9 I have shown the firing pin 11 as being round in cross section, and its surface roughened as is the surface of a file, as indicated at 19, the edges of the facets serving to rupture the particles of compressed explosive when the pin is caused to penetrate such mass. 115

What I claim is:

1. The herein described processes of detonating a charge of explosive, which consists in compressing an explosive, that is highly sensitive to shock and heat when not compressed, to a very high degree, whereby it 120 becomes relatively inert and safe to handle, forming this compressed explosive into a primer and puncturing such primer and rupturing the particles of the compressed explosive, whereby it is fired producing detonating waves of extreme violence. 125

2. As means for detonating a charge of explosive, a charge of an explosive that is highly sensitive to shock and heat when not compressed and which at a very high com- 130

pression becomes relatively inert and safe to handle, compressed to a degree that renders it inert and safe to handle, and a firing pin adapted to engage directly with the said compressed explosive, having a sharp point that will puncture such explosive, and having also edges extending from its pointed end toward its base.

3. In a fuse, a container carrying a charge 10 of an explosive that is highly sensitive to shock and heat when not compressed and which at a very high compression becomes relatively inert and safe to handle, compressed to a degree that renders it inert and safe to 15 handle, and a firing pin having a sharp point and edges extending from the point toward its base, arranged to penetrate the com-

pressed explosive in the said container, the said parts—the container carrying the explosive charge and firing pin—being relatively movable toward each other.

4. As a means for detonating a charge of explosive, a mass of explosive that is highly sensitive to shock and heat when not compressed and which at a very high compression becomes relatively inert and safe to handle, compressed to a degree that renders it inert and safe to handle and a firing pin, having a sharp point adapted to puncture such mass and having edges in rear of the point adapted to rupture the particles of the mass as the pin is caused to enter the mass.

CHARLES P. WATSON.
